UNITED STATES PATENT OFFICE.

LESTER E. TERRY, OF SOUTHAMPTON, NEW YORK.

CESSPOOL.

1,155,970.

Specification of Letters Patent.

Patented Oct. 5, 1915.

Application filed August 29, 1911. Serial No. 646,617.

To all whom it may concern:

Be it known that I, LESTER E. TERRY, a citizen of the United States, and a resident of Southampton, in the county of Suffolk 5 and State of New York, have invented a new and Improved Cesspool, of which the following is a full, clear, and exact description.

The object of the present invention is to 10 provide a cesspool, which, while possessing in a great degree strength and durability, will retain substantially solid matter and permit the escape therefrom and drainage into the surrounding earth of substantially 15 liquid matter.

My invention is hereinafter described and the features of novelty specifically pointed out.

Reference is to be had to the accompanying 20 drawings, constituting a part of this specification, in which similar characters of reference denote corresponding parts in all the views and in which—

Figure 1 shows a cesspool embodying the 25 invention, the view showing a vertical section through one of the diameters; Fig. 2 shows a horizontal section of a portion of the wall; and Fig. 3 shows in perspective, one form of integral units of which the wall 30 may be built.

In the drawing, 1 is a cesspool or similar 35 separating container comprising a wall 2, this wall being preferably circular in cross section and of the desired diameter and height to produce a substantially cylindrical container of the capacity required. The wall 2 is provided with openings 3 leading from the inside to the outside of the wall, and as shown in the drawing, these openings 40 are preferably arranged horizontally and in concentric lines. The openings 3 in practice will be filled with a granular filling 4 through which the liquid may percolate, but which will prevent the solids from passing 45 through the wall. As specifically shown, the wall is built up of a plurality of integral cellular units which advantageously may be in the form of rectangular tiles 5 formed of a vitreous material baked or otherwise cured 50 to secure hardness and durability, and preferably having an outer wall 6 with the in-

tegral partitions 7 and 8 extending between the wall 6 at right angles to each other and forming the longitudinally extending cells 9. As shown in the drawing, these integral 55 units are laid in tiers and in a circular form. After being built up to a sufficient height and preferably upon a bed of sand 10, the outer surface of the wall is surrounded by a packing of sand 11, which in the case of 60 rectangular units, enters between adjacent integral units 5 forming wedge-shaped fillers 12, and sand is also packed within the cellular chambers 9 forming the filtering 65 plugs 4. The granular filling plugs 4 are made of sand or similar material, and will 70 be inclined at the inner ends of the cellular openings, the inclination extending from the bottom to the top substantially at an angle of forty-five degrees. The inner ends of the 75 hollow tiles 5 in each horizontal tier are in contact and the triangular spaces between their outer diverging portions are filled with sand which forms an inward extension of the filtering body 11 surrounding the tiles. 80 In practice, it will be found that only a small portion of the inner ends of the filling plugs will become impregnated with the relatively solid matter, and in cleaning the cesspool, it is only necessary to remove a small portion 85 of the inner ends of the filling plugs and replace with new material.

As is usual in such constructions, the cesspool will have a suitable top or crown 13, and a man hole 14, also a pipe 15 will lead 85 into the cesspool and preferably through the crown 13.

Having thus described my invention, I claim as new and desire to secure by Letters Patent:

1. An earth inclosed sewage receptacle comprising a circular wall built up of cellular open-end tiles laid horizontally and radially upon each other in tiers, and a vertical body or jacket of mineral matter in 95 granular form which incloses and surrounds the outer end of said tiles, the same being thus interposed between the tiles and the earth wall, said material also extending into and partly filling the tile passages, as described.

2. An earth inclosed sewage receptacle

comprising a circular wall built up of cellular open-end tiles laid horizontally and radially one upon another, and a vertical surrounding body of mineral material in 5 granular form, which fills the triangular spaces between the tiles and projects into the tiles themselves, as described.

In testimony whereof I have signed my name to this specification in the presence of two subscribing witnesses.

LESTER EMORY TERRY.
